(57) CLAIM

The ornamental design for a dining chair, as shown and described.

DESCRIPTION

FIG. 1 is a front and perspective view of a dining chair showing my new design;

FIG. 2 is a front and perspective view thereof;

FIG. 3 is a front side view thereof;

FIG. 4 is a back side view thereof;

FIG. 5 is a right side view thereof;

FIG. 6 is a left side view thereof;

FIG. 7 is a top view thereof;

FIG. 8 is a bottom view thereof; and,

FIG. 9 is a rear and perspective view thereof.

The broken lines are for environmental purposes only, and form no part of the claimed design.

1 Claim, 8 Drawing Sheets(56)
